UNITED STATES PATENT OFFICE

2,604,859

SHOE SEWING MACHINE

Alfred S. Clark, Beverly, Mass., assignor to United
Shoe Machinery Corporation, Flemington, N.J.,
a corporation of New Jersey

Application November 16, 1948, Serial No. 60,209

8 Claims. (Cl. 112—34)

1

The present invention relates to McKay shoe sole sewing machines and more particularly to sewing devices for a straight hook needle machine having a rotary shoe supporting horn in which the stitch forming devices, except for a needle threading whirl, are located at the opposite side of the work from the horn. An example of a machine of this type is disclosed in United States Letters Patent No. 710,612, granted October 7, 1902, upon application of E. P. Richardson, No. 1,114,287, granted October 20, 1914, upon application of E. J. Ray and No. 1,738,778, granted December 10, 1929, upon application of B. T. Leveque.

In a shoe being sewn by a machine of the type disclosed in the patents, the sole, upper and insole are attached with stitches passing through the parts while the shoe is being presented to the stitch forming devices without the use of a supporting last. To support the parts of the shoe being sewn the horn enters within the shoe and is bent laterally to one side of the needle to enable the horn to enter into the extremity of a shoe toe while the sole is kept approximately level. The horn has a circular work supporting portion on its tip of suitable dimensions to provide an enclosure for a small needle threading whirl. While sewing about the toe of a shoe the horn is turned with the shoe, the shoe being fed by a feed point or awl to carry the seam around the toe. Between feeding movements of the shoe, the shoe sole is clamped against the horn by a presser foot which engages the sole at a point separated a stitch length from the point of needle operation. The usual arrangement is for the needle, the feed point and the presser to engage the shoe sole serially along the line of the seam, the feed point being located between the needle and the presser foot. The presser foot therefore is separated from the needle path more than the length of a stitch. Because of the separation of the presser foot from the point of needle operation it frequently does not engage the shoe sole directly above the work engaging surface of the horn tip. It is essential therefore to have the presser foot engage the shoe sole with substantially greater pressure in order to resist displacement of the shoe from the horn during stitch formation than would be necessary if the presser foot were directly above the horn tip. By reason of the pressure of the presser foot considerable resistance may be imparted to the turning movement of the shoe. Furthermore, there is a tendency for the presser foot to indent the surface of the sole and to form permanent

2

markings which do not add to the saleability or appearance of the shoe.

The objects of the present invention are to simplify and improve the machine of the patents above referred to in such way that the sole of a shoe being sewn may effectively be clamped against the work supporting horn with a much lighter pressure than heretofore employed for this purpose and may be guided about the curved portions of a shoe sole, particularly about the toe of a shoe, more readily than with prior machines and with the exercise of less skill and ability on the part of the operator than is customarily required.

15 A further object of the invention is to simplify and improve the presser of a McKay type, rotary horn shoe sole sewing machine and to provide an arrangement of the operating parts which will relieve substantially the crowded relationship of 20 the stitch forming devices about the sewing point and still further to provide in the machine a novel and improved form of thread cutter.

25 To these ends, the present machine is equipped with a presser in the form of a frusto-conical roll mounted for rotation about an axis intersecting the path of the reciprocating hook needle for engagement with the shoe of that part of the conical roll surface having its greatest diameter portion close to the needle at one side of the seam line 30 and directly above the work engaging surface of the horn, instead of being spaced along the seam line as in the case of the usual machine of this type. Such construction enables a direct clamping engagement of the presser roll with the shoe sole opposite to and directly above the circular shoe supporting portion of the horn rather than at a point separated horizontally from that part of the shoe sole engaging the horn. By such arrangement, less pressure is required of the 35 presser to secure the shoe sole in position, the pressure being exerted at a more advantageous location closer to the needle. Furthermore, the use of a roll gives direction to the movement of the shoe during feeding and renders the effort 40 of guiding the shoe less burdensome. In this respect a further feature of the invention comprises an edge gage roll rotatably mounted along the seam line about an axis opposite the needle path. The use of such edge gage rolls in combination 45 with a presser roll enables easy turning movement of the shoe with the horn, particularly when the presser roll engages the shoe sole with a clamping pressure exerted at the same side of the needle path with the edge gage roll. For double 50 row sewing the edge gage roll is readily adjustable

into either of two predetermined positions. Accordingly, in the illustrative embodiment of the invention hereinafter described, the edge gage roll is carried by a slide mounted in a guideway and provided with a pair of separate latches arranged to be released simultaneously.

These and other features of the invention consist in the constructions, combinations and arrangements of parts hereinafter described and claimed, the advantages of which will readily be apparent from the following description taken in connection with the accompanying drawings, in which

Fig. 1 is a view in front elevation of a sewing head and a portion of a rotary work supporting horn in a machine embodying the features of the present invention;

Fig. 2 is a perspective detail view of the straight hook needle in the machine of Fig. 1, the upper end of the work supporting horn and the thread cutter in inoperative position, illustrating the relationship of the parts;

Fig. 3 is a similar view showing the thread cutter in operative position;

Fig. 4 is a perspective detail view of a modified form of thread cutter in operative position;

Fig. 5 is a plan view on an enlarged scale of the edge gage and its readily adjustable mounting;

Fig. 6 is a view in right side elevation of the edge gage and adjustable mounting, together with the presser roll and upper portion of the rotary horn showing the manner of guiding a shoe;

Fig. 7 is a view in front elevation of the presser and edge gage rolls; and

Fig. 8 is a sectional view taken along the line VIII—VIII of Fig. 6.

The machine illustrated in the drawings is of the same construction and mode of operation, except as hereinafter pointed out, as that disclosed in the Richardson and Ray patents above referred to. Referring to Fig. 1 of the drawings, the straight hook needle is indicated at 2, the rotary shoe supporting horn at 4, and the feed point at 6. Other stitch forming devices also are provided acting during sewing to draw loops of thread through the work and to set each stitch by tightening the loops against the work. The horn 4 is shaped at its upper work engaging end with a circular shoe supporting portion 8 (Fig. 3), having a needle receiving opening at its center about the axis of which the horn rotates. The upper end of the horn is inclined to enter the toe of a small sized shoe so that in turning the shoe the horn rotates with it about the path of the reciprocating needle as a center without changing the relationship of the circular work supporting portion 8 of the horn tip with the needle. The feed point 6 engages the work a stitch length in advance of the needle path and moves to bring the indentation formed thereby into line with the needle path.

In the machine of the patents above noted, a presser foot engages the surface of the shoe sole, similar to that indicated at 10, along the line of the seam more than a stitch length in advance of the needle path to provide space for the operation of the feed point. For this reason, the presser foot may engage the shoe sole 10 outside the area of the sole supported by the circular portion 8 on the horn. Even under the most favorable conditions with the machine adjusted for inserting relatively short stitches, the movements of the feed point require a location of the presser foot to engage the shoe sole barely within

the edge of the area supported by the portion 8. To insure a suitable clamping action of the presser foot in the patented machines, therefore, a heavy spring pressure is required and the presser foot is locked securely in clamping position to avoid any possibility of displacement of the work during stitch formation.

Instead of locating the work clamping member along the line of the seam in advance of the feed point, the shoe sole, in the machine of the present invention, is engaged by a clamping member close to the needle at the rear side of the seam line opposite the circular shoe supporting portion 8 of the horn. To this end the sole is engaged by a presser roll 12 of frusto-conical shape mounted for rotation about an inclined axis intersecting the path of the reciprocating needle and with that part of the conical roll surface having the greatest diameter disposed to engage that area of the sole supported by engagement with the portion 8 of the horn a substantial distance inside the edge of said portion. Because the presser roll engages the shoe sole much closer to the needle path than does the presser foot of the prior machines, a clamping engagement of greater effective extent is obtained along the sole and far less pressure is required to maintain the sole in clamped position. Accordingly, a small fraction only of the spring pressure exerted on the presser foot in prior machines is required for obtaining a clamping action by the presser roll in the present machine. Furthermore, it is no longer necessary to lock the presser roll in engagement with the work during the formation of each stitch, the presser foot locking parts and their actuating mechanism disclosed in the prior patents being eliminated from the present machine.

In the prior patented machines the presser foot engages the work in line with the seam and in advance of the feed point so that as the feed point operates it draws the sole beneath the presser foot and tends during work feed to maintain, through frictional drag on the sole, a uniform straight line movement of the shoe past the sewing point. The change in location of clamping pressure in the present arrangement of the presser roll is compensated for by rotation of the roll giving direction to the feeding movement even though the roll is disposed at one side of the seam line and the awl acts in feeding the shoe to bring its indentation into a position opposite to the portion of the presser roll circumference engaging the shoe.

To assist the straight line feeding action in the present machine and to reduce any tendency of a one-sided frictional drag on the shoe sole during feed, the present machine is provided with an edge gage roll 14 having an adjustable mounting carried by a bracket 16 substituted for the presser foot of the patented machines. As with the presser foot of the patented machines, the bracket 16 is secured to the lower end of a presser foot bar 18 slidably mounted in the frame of the machine for clamping movement toward and from the work. The bracket 16 is formed with a laterally projecting slotted arm through which a clamping stud 20 is inserted to secure the bracket to the presser bar. The presser roll 12 rotates about a shoulder screw 22 secured in a downwardly extending arm of the bracket 16.

The edge gage roll 14 is rotatably mounted in a novel and improved manner for convenient adjustment on the bracket 16 to move toward and from the needle path so that a greater or less

margin between the seam and the edge of the shoe sole may be provided. In its illustrated form, this mounting is quickly shiftable to either of two positions so that a double row of stitches may be inserted and that the change from one row to the other may easily be accomplished without stopping the machine. The adjustable mounting for the edge gage roll 14 comprises a guideway 24 in the bracket 16. The guideway 24 is disposed substantially at right angles to the path of the reciprocating needle and supports an elongated slide 26 of T section upon which the edge gage roll is rotatably mounted. The rearward end of the slide 26 is provided with a concavity 28 forming a finger grip portion by means of which the slide may conveniently be moved forwardly or rearwardly within its guideway.

To secure the slide 26 in either of two positions, the slide has pivotally mounted upon it a pair of separate latches 30 by a pin 32 passing through a pair of upstanding flanges on the slide, the rearward ends of which latches are bent in opposite directions into a horizontal plane to provide thumb releasing pads 34. The releasing pads 34 are located side by side directly above the finger grip concavity 28 so that in gripping the slide both latches may be moved to releasing positions in a single grasping movement. The forward ends of the latches 30 are bent away from each other and are arranged to engage selectively with a pair of similar notched blocks 36 slidably mounted in reverse relationship within fixed guideways of a box-like portion of the bracket 16. The guideways for the blocks are formed by the inner surfaces 38 of the box-like portion of the bracket 16 and are disposed in parallel relation to the guideway 24 for the edge gage slide 26. To press the latches 30 yieldingly against the blocks the pads 34 are engaged by a pair of coil springs 39 surrounding pins 40 secured to the pads and passing loosely through openings in the slide.

For limiting the forward and rearward movements of the cooperating latches 30 the notched blocks 36 each has a shoulder at one side of each notch, but in reverse relationship to each other. The shoulders 41 are so arranged that the latches may move a limited distance in either direction along their blocks 36 and selectively into and out of the notches of the respective blocks. The blocks are also provided with latch raising cams 42 forming the latch receiving notches with the shoulders 41, the blocks being disposed relatively to each other in opposite directions.

The positions of the blocks 36 may be adjusted to increase or decrease the margins of the seams directed by the edge gage roll 14. For this purpose, the blocks 36 are provided with threaded openings through which pass threaded spindles 44 rotatably mounted in the ends of the box-like portion of the bracket 16. At the forward end of the box-like portion the threaded spindles 44 are held against lengthwise movement in one direction by enlarged heads 46 on the spindles engaging the forward end of the box-like portion. The rearward ends of the spindles are provided with thumb wheels 47 for rotating the spindles and retaining them from endwise movement in the other direction.

As has been stated, the arrangement of the presser roll 12 along the seam line opposite the needle path and the elimination of the presser foot enables the use of an improved form of thread cutter. The thread cutter is manually

actuated and is guided accurately to sever one side of a loop 48 of thread retained on the needle after formation of the last stitch in a seam. By this arrangement the thread is severed close to the last formed stitch 50 while leaving sufficient thread between the needle and the horn to insure proper formation of the first stitch in the new seam.

The thread cutter comprises a knife 52 mounted to swing toward and from the needle path and to enter between the sides of the loop of thread 48 on the needle. The thread cutter knife is in the form of a flat blade, pointed at its cutting end with its forwardly facing edge at the point sharpened while the rearward edge remains unsharpened to avoid severing both sides of the needle loop. The knife is secured in a slot of a block 54 fastened to the lower end of a reversely bent lever 56. The lever extends upwardly from the block 54 to a right angle bend, thence horizontally to a fulcrum stud 58 and then upwardly to a handle portion. The stud 58 projects from a plate 59 clamped to the presser foot bar 18. The handle portion of the lever 56 also carries a stop clip 60 adjustably secured by a screw 61 passing through a slot in the clip, so arranged that the clip will engage the presser foot bar to limit the thread cutting movement of the knife 52 and prevent it from engagement with the other operating parts of the machine. The lever 56 is normally held in an inoperative position with the knife retracted out of the needle path by a tension spring 62 connected between a pin on the lever 56 and a pin of the machine frame.

To guide the movements of the knife 52 and to insure accurate entry between the sides of the loop 48 of thread carried by the needle, a second slot in the block 54 above the knife 52 supports a forked guide member 64 in parallel relation to the blade of the knife. The fork in the guide member provides an opening of sufficient width to fit the diameter of the needle so that when it engages the needle the point of the knife is positioned without fail between the sides of the needle loop.

To prevent damage to a shoe bottom by engagement with the knife 52 the cutting edge of the knife is surrounded by the arms of a guard plate 66. The guard plate 66 has one arm curved beneath and upwardly over the cutting edge of the knife and another arm bent into a horizontal position to extend behind the needle loop and beyond the point of the knife to prevent accidental contact by the hands of the operator or by the work with the knife point.

In another form of the knife a guard plate is found unnecessary inasmuch as the forward edge of the knife is left unsharpened, the rearward edge only being employed to sever the thread. Such knife is indicated at 68 in Fig. 4 and is mounted in the same manner as in the previous arrangement within the lower slot of the block 54. The same guide member 64 also is employed with the unguarded knife 68. In this instance, however, the knife is so shaped that during its cutting stroke the rearward edge of the knife does not move rearwardly beyond the central axis of the needle. Also, the use of a sharpened point on the knife is eliminated so that no guard is required in this instance for the point.

Certain features of the invention relating to improvements in Thread Cutters are claimed in a divisional application Ser. No. 129,033, filed

November 23, 1949 in the name of the present inventor.

The nature and scope of the invention having been indicated and a particular embodiment having been described, what is claimed is:

1. A shoe sewing machine having a reciprocating straight hook needle and other stitch forming devices, a rotary shoe supporting horn and a presser roll positioned in proximity to the shoe-supporting horn so as to engage a shoe supported by said horn, said presser roll being mounted for rotation about an axis intersecting the path of the reciprocating needle, in combination with an edge gage roll positioned adjacent said presser roll so as to engage an edge of a shoe supported by said horn, said edge gage roll being mounted for rotation about an axis parallel to the needle path.

2. A shoe sewing machine having a reciprocating straight hook needle and other stitch forming devices, a rotary shoe supporting horn, a presser and an edge gage, in combination with a slide on which the edge gage is mounted, a guideway for the slide disposed substantially at right angles to the path of the reciprocating needle, and a pair of separately actuated latches operatively connected to said guideway and slide for securing the slide in either of two positions.

3. A shoe sewing machine having a reciprocating straight hook needle and other stitch forming devices, a rotary shoe supporting horn, a presser and an edge gage, in combination with a slide on which the edge gage is mounted, a guideway for the slide disposed substantially at right angles to the path of the reciprocating needle, a pair of separate latches mounted on the slide, and separately adjustable notched blocks mounted with respect to the slide for engagement by the latches and into the notches of which blocks the latches enter selectively to enable the position of the slide to be changed.

4. A shoe sewing machine having a reciprocating straight hook needle and other stitch forming devices, a rotary shoe supporting horn, a presser and an edge gage, in combination with a slide on which the edge gage is mounted, a guideway for the slide disposed substantially at right angles to the path of the reciprocating needle, a pair of separate latches mounted on the slide for securing the slide selectively in either of two positions, blocks having latch receiving notches, said blocks being positioned in fixed guideways which are parallel to the guideway for the edge gage slide, and threaded spindles passing through the blocks to change the two positions of the edge gage.

5. A shoe sewing machine having a reciprocating straight hook needle and other stitch forming devices, a rotary shoe supporting horn, a presser and an edge gage, in combination with a slide on which the edge gage is mounted, a guideway for the slide disposed substantially at right angles to the path of the reciprocating needle, a pair of separate latches mounted on the slide for securing the slide selectively in either of two positions, notched blocks having shoulders for stopping the movements of the latches and for causing the latches to enter the notches of the blocks, said blocks being positioned in fixed guideways which are parallel to the guideway for the edge gage slide, and yielding means for pressing the latches against the

blocks, said latches having adjacent oppositely disposed pads for enabling the latches to be disengaged from the blocks simultaneously and the slide to be shifted in the guideway without releasing the grasp on the latches.

6. A shoe sewing machine having a reciprocating straight hook needle and other stitch forming devices, a rotary shoe supporting horn, a presser and an edge gage, in combination with a slide on which the edge gage is mounted, a guideway for the slide disposed substantially at right angles to the path of the reciprocating needle, a pair of separate latches mounted on the slide for securing the slide selectively in either of two positions, notched blocks positioned in fixed guideways which are parallel to the guideway for the slide, and yielding means for pressing the latches against the blocks, said blocks each having a shoulder at one side of a notch to limit the movements of the latches along the blocks in either direction while enabling the latches to engage selectively with the notches in the respective blocks.

7. A shoe sewing machine having a reciprocating straight hook needle and other stitch forming devices acting during sewing to draw loops of thread through the work, and a rotary shoe supporting horn having a circular shoe supporting portion of restricted area surrounding the reciprocating path of the needle, in combination with a frustro-conical presser roll mounted for rotation about an axis intersecting the path of the reciprocating needle, said presser roll being positioned adjacent the circular shoe-supporting portion of the horn for engagement of that part of the conical surface of the presser roll having the greatest diameter, with the shoe close to the needle at one side of the line of the seam opposite the circular shoe supporting portion of the horn to clamp the shoe against the horn.

8. A shoe sewing machine having a reciprocating straight hook needle and other stitch forming devices acting during sewing to draw loops of thread through the work, and a rotary shoe supporting horn having a circular shoe supporting portion of restricted area surrounding the reciprocating path of the needle, in combination with a frustro-conical presser roll mounted for rotation about an axis intersecting the path of the reciprocating needle, said presser roll being adjacent the circular shoe-supporting portion of the horn for engagement of that part of the conical surface of the presser roll having the greatest diameter, and a feed point acting in advance of the needle path within the seam line to feed the shoe to a position with an indentation formed thereby opposite to that portion of presser roll engaging the shoe.
